(Cl. D22—5)

To all whom it may concern:

Be it known that I, Erwin Krusius, a citizen of Germany, residing at Solingen, Germany, have invented a new, original, and ornamental Design for Scissors, of which the following is a specification, reference being had to the accompanying drawing, forming part thereof.

This is a continuation-in-part of my co-pending application filed on August 14, 1951, under Serial Number D. 16,261, and now abandoned.

Fig. 1 is a top plan view of scissors showing my new design;

Fig. 2 is an edge view thereof;

Fig. 3 is a bottom plan view as they appear in partly opened position;

Fig. 4 is a cross section taken on line 4—4 of Fig. 1;

Fig. 5 is a cross section taken on line 5—5 of Fig. 1; and

Fig. 6 is a cross section taken on line 6—6 of Fig. 1.

The essential features of my design reside in the portions shown in solid lines on the drawing.

I claim:

The ornamental design for scissors, substantially as shown and described.
